UNITED STATES PATENT OFFICE.

FERDINAND CHARRON AND LÉONCE GIRARDOT, OF PARIS, FRANCE.

CAP FOR NAVES OF WHEELS.

SPECIFICATION forming part of Letters Patent No. 739,830, dated September 29, 1903.

Application filed April 22, 1902. Renewed July 24, 1903. Serial No. 166,911. (No model.)

To all whom it may concern:

Be it known that we, FERDINAND CHARRON and LÉONCE GIRARDOT, citizens of the Republic of France, residing at No. 45 Avenue 5 de la Grande Armée, Paris, in the Republic of France, have invented a certain new and useful Improved Cap for Naves of Wheels, of which the following is a specification.

Our invention relates to an improved cap 10 for naves of wheels, particularly characterized by the arrangement which allows of renewing the oil provision without unmounting said cap. For this purpose the cap, which is directly screwed on the nave, is provided at 15 a point of its periphery with a filling-hole closed by a suitable plug. To empty the old oil, the wheel is caused to turn till the plug is at the bottom. The plug is then removed, and as soon as the old oil has flowed out the 20 wheel is caused to turn again, so that the hole of the cap be brought to the top, whereby the necessary quantity of new oil may be poured in the cap-box, and the plug is then replaced in position.

25 In the accompanying drawings, Figure 1 is a vertical sectional view of the cap. Fig. 2 is a plan view of same, and Fig. 3 is a modified construction of the plug of the cap.

The cap is screwed by its threaded border 30 *a* in the nave of the wheel and forms inwardly a box or receiver *b* for the oil. Outwardly the cap is formed with a collar *c*, a polygonal portion *d*, adapted to receive a key for screwing and unscrewing said cap, and with a full 35 bottom or back piece *f*.

At a suitable point of the cap, preferably on one of the sides of the polygonal portion *d* and extending through the thickness of said cap, is provided a screw-threaded hole *o* for 40 pouring in or emptying the oil. This hole is closed by means of a screw-plug *v*, with a beveled head, a washer *r*, of leather or any suitable material, being interposed between the cap and the plug to assure the tightness of the 45 closing.

In order to prevent any accidental unscrewing of the plug by trepidations, two lugs *m* are provided at each side of the hole *o*. These

lugs are formed with openings in which is inserted, once the plug *v* is in place, a pin *g*, 50 engaging the slot of the head of the plug.

We may for the same purpose, and to be sure that it will always be possible at the end of the screwing of the plug to bring a slot of the head of said plug opposite the pin, provide on said head several diametrical slots 55 *x*, making a certain angle between them, as shown in Fig. 3.

Having now particularly described and ascertained the nature of our said invention and 60 in what manner the same is to be performed, we declare that what we claim is—

1. A lubricating-cap for vehicle-wheels consisting of a hollow metallic block opened at the side where it is screwed to the nave and 65 having on its polygonal periphery *d* a screw-threaded hole *o* for the pouring in and the emptying of the oil, and two perforated lugs *m* arranged at each side of the hole, in combination with a plug *v* adapted to be screwed in 70 the hole *o* and a leather washer *r* arranged beneath the head of the plug, and in combination with a pin *g* extending through both lugs *m* and partially engaging a slot of the head of the plug, substantially as and for the 75 purpose set forth.

2. A lubricating-cap for vehicle-wheels consisting of a hollow metallic block opened at the side where it is screwed to the nave and having on its periphery a screw-threaded hole 80 *o* and two perforated lugs *m* arranged at each side of the hole, in combination with a plug *v* adapted to be screwed in the hole *o* and the head of which is provided with several diametrical slots *x*, in combination with a pin *g* 85 extending through the lugs *m* and engaging one of the slots *x*, substantially as and for the purpose set forth.

In witness whereof we have hereunto set our hands in presence of two witnesses.

FERDINAND CHARRON.
LÉONCE GIRARDOT.
